(57) CLAIM

The ornamental design for an adhesive application system, as shown and described.

DESCRIPTION

FIG. 1 is a perspective view of an adhesive application system showing my new design;

FIG. 2 is a left side view of the system shown in FIG. 1;

FIG. 3 is a right side view of the system shown in FIG. 1;

FIG. 4 is a front view of the system shown in FIG. 1;

FIG. 5 is a rear view of the system shown in FIG. 1;

FIG. 6 is a top plan view of the design shown in FIG. 1; and,

FIG. 7 is a bottom plan view of the design shown in FIG. 1.
